(57) **CLAIM**

The ornamental design for a flash drive, as shown and described.

DESCRIPTION

FIG. 1 is a perspective view of a flash drive showing my design;

FIG. 2 is a front elevational view thereof;

FIG. 3 is a left-side, elevational view thereof;

FIG. 4 is a right-side, elevational view thereof;

FIG. 5 is a top plan view thereof;

FIG. 6 is a perspective view of FIG. 1 with a plug portion rotated 90 degrees; and,

FIG. 7 is a perspective view of FIG. 1 with the plug portion rotated 180 degrees.
